UNITED STATES PATENT OFFICE

MARTIN L. NELSON, OF PARK RIDGE, ILLINOIS, ASSIGNOR, BY MESNE ASSIGNMENTS, TO ASSOCIATED ELECTRIC LABORATORIES, INC., OF CHICAGO, ILLINOIS, A CORPORATION OF DELAWARE

MULTIOFFICE TELEPHONE SYSTEM

Original application filed July 6, 1922, Serial No. 573,175. Divided and this application filed July 2, 1927. Serial No. 203,086.

The present invention relates in general to multi-office telephone systems, but more in particular to systems of this character in which registering mechanism is employed for registering telephone numbers as they are called, in combination with translating and sending mechanism for routing the calls to their destinations, and the main object is to produce a new and improved "director", which may be considered as an improvement on the director shown and described in the British Patent 194,580. Although, as stated, the invention is applicable generally to multi-office systems of the type mentioned, as to a large number of features it is especially adapted for use in a multi-office system comprising both automatic and manual offices.

It is common practice, when converting a multi-office manual system to automatic operation, to replace the manual equipment by automatic equipment one office at a time, the transition period often extending over a period of several years. Accordingly, during the time when some of the offices are being operated automatically and others manually, arrangements must be made whereby the entire system may operate as a unit. The director shown in the present application is designed for use in an automatic office of a mixed office multi-office system comprising two or more automatic offices, an individual line manual office, and a party line manual office. Calls are trunked from one automatic office to another according to standard automatic practice, while calls from an automatic office to the manual offices are preferably handled by calls indicating apparatus adapted to display the called numbers to operators according to the general principles set forth in the U. S. Patent 1,475,590, granted Nov. 27, 1923 to Martin and Willis.

In a complex system of the foregoing character it will generally happen that the telephone numbers are not uniform throughout all the offices as to the number of digits, and a special object of the invention, therefore, is the provision of a director which is adapted to set up connections to various offices of the type mentioned irrespective of the number

of digits in the telephone numbers. While various kinds of numbers may be taken care of, a system will be assumed by way of example, in which the numbering scheme for each of the automatic offices is laid out according to the jack per station plan, according to which plan the subscriber's number comprises only four digits, whether the subscriber is a party line subscriber or an individual line subscriber; in which the party line manual office numbering scheme is such that each subscriber's number comprises four digits for determining the called line and a fifth digit for determining the desired subscriber on the called line; and in which the individual line manual offices are equipped with the same kind of call indicators at the incoming call indicator "B" positions as are used in the party line manual offices, which call indicators require five digits to be called in the subscriber's number before the number is displayed to the operator. In the individual line manual offices, the fifth digit lamps are removed from the call indicators and the fifth digit dialled has no function other than to switch the indicator into position to display the four digits of the subscriber's number to the operator. The above arrangement allows the standard five digit call indicators to be in each office of the system, which from a manufacturing standpoint alone, is a considerable advantage.

In the director, suitable circuit arrangements are made such that, when the call is going to an automatic office, the four digits of the subscriber's number are dialled and the director is cut off; when a call is going to a party line manual office, the five digits of the subscriber's number are dialled, whereupon the director is cut off as before; and when a call is being extended to an individual line manual office, the four digits of the subscriber's number are called, and for the purpose of switching the call indicator through, the digit 1 is added by the director, whereupon the director is cut off as before.

Another object of the invention is to provide means whereby the director is auto-

5 matically cut off and the connection switched through to the first selector, if no dialling occurs during a predetermined interval, this being done under the assumption that, since 10 no digits are dialled, the subscriber's line is accidentally short circuited or grounded and, consequently, that the seizure of the director was not due to the subscriber initiating a call; and whereby if no dialling occurs 15 during a predetermined interval after the subscriber has dialled one or more digits, the call is trunked through automatically by the director to the monitoring operator.

10 A further object is the production of circuit arrangements, whereby the office register of the director is automatically rotated one step upon the calling of the digit 0, which is the digit dialled when the long distance operator is desired, so as to place the director in condition to send out the code necessary to trunk the call to the long distance operator.

15 The features pointed out above are claimed in my application, Serial No. 573,175, filed July 6, 1922, of which the present application is a division. The features claimed in this divisional application include the provision of new and improved circuit arrangements for use in connection with a 20 director system whereby service is given to automatic paystation lines.

25 Another object is the provision of circuit arrangements, whereby a paystation subscriber may call the long distance operator without depositing a coin, but cannot obtain connection with a subscriber's line without first depositing a coin, the circuit arrangements being such that the call is trunked through immediately to the monitoring operator, in case the first digit dialled by a paystation subscriber is other than 0, unless he has deposited a coin.

30 A still further feature is the provision of circuit arrangements, whereby the same director may be used by subscribers on paystation lines and by subscribers on other lines, and whereby the director is rendered fully operative automatically independent of any act performed by a subscriber when he is calling from any line other than a paystation line.

35 The other features relate principally to circuit improvements and will become apparent upon a further perusal of the specification.

40 Referring to the drawings, Fig. 1 shows a paystation line extending from the paystation telephone A to the individual line switch C in the exchange; Fig. 2 shows a paystation repeater R accessible to the line of substation A, and a secondary switch SS which has access to a plurality of directors; Fig. 3 shows an ordinary station A', line, individual line switch C', a repeater R' accessible to the subscriber's line switch C', the secondary switch 45 SS', individual to the repeater R', and hav-

ing access to the same directors as the secondary switch SS, Fig. 2, and a first selector D associated with the repeater R'; Figs. 4-7, inclusive, show the improved director; and Fig. 8 is a layout showing how Figs. 1 to 7, inclusive, join together.

45 The automatic substation A, Fig. 1 has the usual talking, signalling, and switch control instrumentalities, and being a paystation telephone, has coin controlling and coin controlled mechanism. The substation A', Fig. 3, is similar to the substation A, except that the circuit is somewhat simpler and no coin mechanism is provided.

50 The line switch C, Fig. 1, in which the line of substation A terminates is of the well-known rotary type in which the wipers have no normal position and move in a forward direction only. The line switch C', Fig. 3, is identical with the line switch C.

55 The repeater R', Fig. 3, which is inserted in the trunk ahead of the first selector D, is provided for the purpose of repeating the number dialled by the calling subscriber into the director and for repeating from the director into the automatic switches. The repeater R, Fig. 2, is similar to the repeater R', with the exception that the repeater R, being a paystation repeater, has arrangements for deferring the grounding of a certain conductor in the director trunk until the calling subscriber has deposited a suitable coin. The repeater R has also the usual arrangements for collecting or refunding the coin when the calling subscriber hangs up.

60 The secondary switch SS, Fig. 2, is mechanically identical with the line switch C or the line switch C', and has its circuits suitably arranged for selecting an idle director when the trunk with which it is associated is seized. The secondary switch SS' is mechanically identical with the secondary switch SS and has practically the same circuit. Such differences as exist will become apparent when the hereinafter given detailed description is 65 read.

65 The secondary switches SS and SS', together with the other secondary switches in the same secondary group, have access to a plurality of directors such as the one shown in Figs. 4-7, inclusive, by way of four conductor trunks such as the one comprising conductors 101-104, inclusive. The director accessible by way of this latter trunk comprises, in addition to various controlling relays, the master digit controller MDC, Fig. 4; the office register OR, and the intermediate distributing frame IDF, Fig. 5; a sequence switch S, Fig. 6; the digit registers DR-DR⁴, inclusive, Fig. 7; and the sender which comprises certain relays shown in Fig. 6 and the counting relays shown in the lower part of Fig. 7.

70 The master digit controller MDC, Fig. 4, is mechanically a so-called minor switch and has a pair of wipers 253 and 254 which are 75

moved in a forward direction by stepping magnet 251, and which are released to normal by release magnet 250. Off normal contacts 228 are provided for the purpose of opening 5 the circuit of release magnet 250 when the wipers reach normal position. The digit registers DR-DR⁴, inclusive, are each mechanically identical with the master digit controller MDC, with the exception that the wipers of the digit registers are normally out of 10 engagement with their associated bank contacts, whereas the wipers of the master digit controller are normally in engagement with the first associated bank contacts. A further 15 difference is that each of the digit registers is provided with only one wiper and each has an extra pair of off normal contacts, as shown. 20 The office register OR, Fig. 5, is a Strowger switch of the vertical and rotary type, having 100 sets of contacts arranged in ten horizontal rows or levels. This switch is directly controlled in its vertical and rotary movements by impulses delivered to its vertical and rotary magnets by way of the master digit controller MDC. This office register is provided with four wipers 260-263, inclusive, which have access to each of the 100 sets of bank contacts, of which four sets are shown. 25 The vertical, rotary, and release magnets of the switch are indicated by the reference characters 229-231, inclusive, respectively. This switch is provided with an off normal combination comprising spring 232 and its upper contact and also the normally open contacts 30 controlled by spring 232. The normally open contacts controlled by spring 232 are adjusted to close when the switch wipers are raised opposite the first level of bank contacts. Spring 232, however, does not break away 35 from its associated lower contact and come into engagement with its upper contact until the wipers of the switch are raised opposite the second level of bank contacts. This adjustment enables circuit arrangements to 40 be made, whereby the switch is released each time it comes to rest opposite the first level of bank contacts, which level of contacts is left dead and does not correspond to any office numbers. The switch OR is provided also 45 with the tenth level spring combination comprising springs 233-235, inclusive, which are operated by the switch shaft when the latter is raised opposite the tenth level of bank 50 contacts. The bank levels 2-9, inclusive, of the office register OR are wired to sets of terminals on the left hand side of the frame IDF. The first level, as before stated, does not correspond to any office numbers and, consequently, is not wired up to the IDF. Of the 55 tenth level of bank contacts, only the first set is wired to the IDF, the nine remaining sets not being used in this particular case. 60 The ten impulse conductors comprising conductors 291-300, inclusive, together with 65 the special conductors 301-306, inclusive, are terminated on the right hand side of the IDF, and each may be multiplied to as many contacts as desired in order to facilitate the running of any desired number of jumpers to each conductor, only one contact for each 70 conductor being shown. The ten impulse conductors represent the digit impulses, the last figure in the reference character applied to each conductor indicating the number of impulses the conductor represents. 75

Of the special conductors 301-303, inclusive, conductor 301 is the switch conductor and is used to switch the director through when the number called is not a subscriber's number, such as, for example, when the long 80 distance operator is being called by the director, by dialling 46.

Conductor 302 is the automatic office discriminating conductor and, accordingly, a 85 jumper is run to it from the fourth bank contact of each set of contacts that represents an automatic office, so as to place the director in condition to send properly and switch through at the right time, the director being set so as to add the digit 1 to the individual line manual numbers so as to switch the call indicators in the individual line manual offices after the four digits of the number are dialled. 90

The fourth contact in each set of contacts 95 that represent a manual party line number is jumpered to conductor 303, so as to place the director in condition to receive and send out the digit corresponding to the desired station on the called party line. 100

Conductors 304-306, inclusive, are the usual skip conductors and are provided for the purpose of causing the sequence switch S, Fig. 6, to advance automatically past the second, third, and fourth positions, respectively, 105 when jumpers are properly run to those conductors.

The sequence switch S, Fig. 5, is a step by step rotary switch of the type in which the wipers move in a forward direction only, and 110 in which the wipers are advanced when the stepping magnet retracts its armature rather than when the stepping magnet attracts its armature.

In the drawings the slow acting relays are 115 denoted by shading the lower portion of their cores, or by making the upper portion of their cores solid black, depending upon whether the relay is merely slow to release or is also slow to operate. The shaded portion on the lower end of the core of a relay indicates that that relay is slow to release after its circuit is opened, but is not appreciably slow to operate upon a closure of its circuit. On the other hand, a solid black portion on 120 the upper end of the core of a relay indicates that that relay is slightly slow to pull up after its circuit is closed, in addition to being slow to release after its circuit is opened. 125

The general object and scope of the invention

tion having been set forth in general in the foregoing, the operation of the equipment shown will now be described more in detail. For this purpose, it will be assumed first that the subscriber at substation A' desires to call a subscriber whose number is 5678, and whose line terminates in the office, the first two letters of which are numerically equivalent to 91, it being understood, of course, that the letters of the alphabet appear on the subscribers' calling devices, and that the subscribers dial the first two letters of the office name.

When the receiver is removed at substation A', a circuit is closed over the associated line conductors for relay 111 of the line switch C'. Relay 111, upon energizing, closes a circuit for switching relay 110 and stepping magnet 112 in series at armature 117, and at armature 116 connects test wiper 119 to the junction of relay 110 and magnet 112. In case the trunk upon which the wipers of the line switch C' are standing is idle, the latter operation has no effect and switching relay 110 energizes immediately. However, assuming the trunk upon which the wipers are standing to be busy, switching relay 110, being short circuited by the ground potential which is present on the test contact thereof, does not energize, and the switch wipers 118-120, inclusive, are automatically advanced step by step in search of an idle trunk by the buzzer like action of stepping magnet 112. When an idle trunk is reached, which trunk it will be assumed is the one comprising conductors 121-123, inclusive, switching relay 110, being no longer short circuited, energizes in series with stepping magnet 112, stepping magnet 112 not energizing at this time on account of the high resistance of switching relay 110. Upon energizing, switching relay 110 opens the test circuit and prepares the holding circuit at armature 114, thereby making the seized trunk busy immediately, and at armatures 113 and 115 disconnects the conductors of the calling line from the winding of line relay 111 and ground and extends them by way of wipers 118 and 120, trunk conductors 121 and 123, and the resting contacts of armatures 131 and 134 and said armatures to the windings of line relay 125 of the repeater R'. Line relay 125, upon energizing, closes a circuit for line relay 137 of the secondary switch SS' at armature 128. Relay 137, upon energizing, disconnects release trunk conductor 122 of the repeater R' from release trunk conductor 161 of the selector D, and places ground on the former at armature 141, thereby establishing the usual holding circuit for the line switch C' before line relay 111 has had time to deenergize; closes a circuit for switching relay 138 and stepping magnet 147 in series at armature 140; and at armature 139 connects test wiper 149 to the junction of switching re-

lay 138 and stepping magnet 147. In case the trunk upon which the wipers of the switch are standing is idle, the last mentioned operation does not have any effect, and switching relay 138 energizes in series with stepping magnet 147. However, assuming the trunk upon which the wipers are standing to be busy, switching relay 138 is short circuited by the ground potential which is present on the test contact thereof, and the wipers 148-151, inclusive, are advanced step by step in search of an idle trunk by the buzzer like action of stepping magnet 147. When an idle trunk is reached, which trunk it will be assumed is the one comprising conductors 101-104, inclusive, test wiper 149 encounters an ungrounded test contact and switching relay 138, being no longer short circuited, energizes in series with stepping magnet 147. Stepping magnet 147, however, does not energize at this time on account of the high resistance of switching relay 138. Upon energizing, switching relay 138 opens the test circuit and places ground on test wiper 149 at armature 144, and at armatures 143, 145, and 146 connects up wipers 148, 150, and 151, respectively. In response to the placing of ground on test wiper 149, conductor 102 is grounded, whereupon relay 204, Fig. 4 energizes; connects the timed impulse lead 209 to the lower winding of relay 201 at armature 217; disconnects ground from the release lead 242 at armature 216; and at armature 215 prepares a locking circuit for relay 201. As a result of the connecting up of wiper 151 of the secondary switch SS', ground is placed on lead 104, thereby grounding the last eight contacts in the lower bank of the master digit control switch MDC, Fig. 4, and closing a circuit for relay 208. Relay 208, upon energizing, disconnects relay 206 from conductor 237 at armature 227. As a result of the connecting up of wiper 150 of the secondary switch SS', relay 127 of the repeater R' is connected up to the outgoing director impulse conductor, whereupon repeating relay 127 energizes over the following circuit: from ground by way of armatures 414 and 417 of relays 381 and 382, Fig. 6, and their resting contacts, conductor 248, resting contact of armature 220 of relay 206, Fig. 4, and said armature, conductor 103, wiper 150, armature 145 and its working contact, and repeating relay 127 to battery. Repeating relay 127, upon energizing, closes a bridge across conductors 160 and 162 of the selector D at armature 136, whereupon line relay 163 of the selector D energizes and closes a circuit for release relay 164 at armature 174. Release relay 164, upon energizing, opens a point in the circuit of release magnet 167 and prepares a circuit for vertical magnet 168 at armature 176, and at armature 175 places ground on release trunk con-

ductor 161. In response to the connecting up of wiper 148 of the secondary switch SS, a connection is extended from armature 129 of line relay 125, by way of armature 143 and its working contact, wiper 148, conductor 101, armature 390 and its resting contact, series relay 202, wiper 253 of the master digit control switch MDC, conductor 249, vertical magnet 229 of the office register OR, and the right hand winding of the trunk tone machine TT to battery. Since armature 129 of line relay 125 of the repeater R' is now attracted, and since that armature is connected with the lower heavy talking conductor through condenser 124, the calling subscriber hears the tone produced by the trunk tone machine TT, Fig. 5, and knows that he may proceed with the call.

Before the establishing of the desired connection is proceeded with, the function of certain equipment shown in Fig. 4 will be taken up more in detail. For this purpose, it will be assumed that the subscriber at substation A' is called away from his telephone after the receiver is removed, and that he does not replace the receiver on the hook. Now, when ground is placed on the common timed conductor 209, Fig. 4, by the associated cam springs, which occurs about every half minute or so, a circuit is closed for the lower winding of the marginally adjusted relay 201, which winding is composed of a small number of turns of wire having a high specific resistance. Consequently, relay 201 energizes sufficiently to operate the lightly adjusted armature 209, but not sufficiently to operate the more stiffly adjusted armature 210. Armature 209, upon being operated, grounds the upper winding of relay 201 by way of armature 215 and its working contact, and the resting contact of armature 212 and said armature. No current flows through the upper winding at this time, however, owing to the fact that it is grounded at both terminals. When ground is removed from the common conductor 209, current flows through the upper and lower windings of relay 210 in series, whereupon the said relay energizes fully, and at armature 210 disconnects the timed impulse lead from its own lower winding, and extends it to relay 376 by way of armature 218 and its resting contact, and the normally closed contacts controlled by armature 389. When the next ground impulse is placed on conductor 209, a circuit is closed for relay 376. Relay 376, upon energizing, locks itself to conductor 102 at armature 389, and at armature 390 disconnects conductor 101 from relay 202 and connects it to ground instead. When this occurs, switching relay 126 in the repeater R', with which conductor 101 is connected, energizes and extends the connection through to the selector D and releases the director in a manner to be described fully hereinafter. This is done so as

to not tie up the director for an undue length of time. The selectors, such as D, are provided ordinarily with timed supervisory means (not shown) which brings in a signal in case a selector is held longer than a predetermined interval without being operated.

It will be assumed now that the subscriber at substation A' is not called away from his telephone, and that he separates his calling device in accordance with the first office digit 9 of the desired number before ground is placed on the common lead 209 the second time, i. e., before relay 376, Fig. 4, is energized. That being the case, line relay 125 of the repeater R' deenergizes in response to each interruption of its circuit at the calling substation, and, upon each deenergization, places ground on conductor 101 at armature 129. Each time ground is placed on conductor 101, an impulse of current is delivered to vertical magnet 229 by way of a previously traced circuit which includes series relay 202, Fig. 4, and wiper 253 of the master digit control switch MDC. By the operation of vertical magnet 229, which receives nine impulses of current at this time, the wipers 260-263, inclusive, of the office register OR are raised step by step until they stand opposite the ninth level of bank contacts. Slow acting series relay 202 is energized during the entire vertical movement of the wipers and, upon energizing, disconnects ground from conductor 241 at armature 212, thereby opening the locking circuit of relay 201 and allowing it to deenergize in case it is energized, and at armature 212 and its working contact closes a circuit for relay 203. Relay 203, upon energizing, prepares a circuit for relay 205 and for stepping magnet 251 of the master digit control switch at armature 214.

At the end of the vertical movement of the switch OR, series relay 202 deenergizes and opens the circuit of relay 203 at armature 212. Relay 203, being slow acting, retains its armature attracted for an interval. As a further result of the deenergization of relay 202, it completes the circuit of stepping magnet 251 of the switch MDC at armature 212. Stepping magnet 251, upon energizing, advances the wipers 253 and 254 into engagement with the second set of bank contacts. Relay 205 energizes in multiple with stepping magnet 251, closes a locking circuit for itself and opens its initial circuit at armature 219; and at armature 218 disconnects the timed impulse lead extension from conductor 243 and connects it to relay 206, thereby preparing the director to call the monitoring operator in case the subscriber waits too long between the dialling of the digits of the number. After an interval, slow acting relay 203 deenergizes and opens the circuit of stepping magnet 230 of the switch MDC. The director is now in readiness to register the second office digit.

In order to explain how the call is trunked through to the monitoring operator in case the calling subscriber delays too long between the dialling of the various digits, it will be assumed that the subscriber does not dial the second digit in the office number within the prescribed time limit. That being the case, relay 201 is energized and is locked up in the hereinbefore described manner the first time ground is placed on the common timed lead 209 after the dialling of the first digit. The next time ground is placed on the common timed conductor 209, a circuit is closed for relay 206 by way of armature 210 and its working contact, and armature 218 and its working contact. Relay 206, upon energizing, places ground on release conductor 242 at armature 221; opens the circuit of repeating relay 127, Fig. 3, at armature 220; opens a point in the circuit of relay 376 at armature 222, disconnects ground from locking conductor 244 at armature 223, so as to allow relay 377, Fig. 6, to deenergize in the event that it is energized; and at armature 224 closes a circuit for relays 207 and 256 in series. In response to the ground potential being placed on release conductor 242, release magnet 231 of the office register OR energizes in series with the normally open contacts controlled by off normal spring 252, whereupon the shaft and wipers of the switch OR are restored to normal position in the usual manner, the circuit of release magnet 231 being opened by the switch shaft when the latter reaches normal position. Likewise, release magnet 250 of the master digit control switch MDC energizes through off normal contacts 228 and restores the wipers 253 and 254 to normal. Relay 207, upon energizing, locks itself to the grounded conductor 102 at armature 225, and at armature 226 connects the resting contact of armature 224 to start conductor 247. Relay 256, Fig. 5, upon energizing in series with relay 207, connects up the four wiper conductors 264-267, inclusive, of the office register OR to the group of special conductors 284-287, inclusive, respectively. The opening of the circuit of repeating relay 127 of the repeater R' is for the purpose of allowing any partly established connection that might be set up to release. Since the connection extends only to the selector D, the line and release relays thereof are deenergized one after the other, whereupon the switch shaft steps up one step and is then restored to normal by the release magnet. When ground is removed from the common conductor 209 after an interval of a second or so, relay 206 deenergizes and places ground on start conductor 247 at armature 224 by way of armature 226 and its working contact, and at armature 220 again closes the circuit of repeating relay 127 in the repeater R', whereupon the line and release relays of the selector D energize again. In response to ground being placed upon start conductor 248,

the sending portion of the director is set in motion, and the number 311 corresponding to the terminals on the right hand side of the IDF to which the special conductors 284-286, inclusive, are jumpered, is sent out in a manner to be described fully hereinafter.

Assuming now that the calling subscriber does not wait too long between the calling of the various digits, and consequently, that he calls the second digit 1 in the desired office number before ground is placed on the common conductor 209 the second time after the dialling of the first digit in the number, one interruption is thereby produced in the circuit of line relay 125 of the repeater R'. Upon deenergizing in response to this interruption, line relay 125 sends an impulse of current over conductor 101. This impulse of current extends by way of a path previously traced to wiper 253 of the master digit control switch MDC, and thence by way of the second associated bank contact, conductor 246, and the contact of the tenth level spring 233 and said spring to rotary magnet 230 of the office register OR. Rotary magnet 230, upon energizing, advances the wipers 260-263, inclusive, into engagement with the first set of bank contacts in the ninth level. By the combined action of slow acting series relay 202 and slow acting relay 203, an impulse of current is delivered, as before, to stepping magnet 251 of the master digit control switch at the end of the calling of the second digit, whereupon the wipers 253 and 254 are advanced into engagement with the third set of bank contacts. Wiper 253, upon coming into engagement with its third associated bank contact, prepares a circuit for stepping magnet 445 of the digit register DR, which register is the one that responds to the calling of the first digit in the subscriber's number, and wiper 254, upon coming into engagement with its associated contact, places ground on start conductor 247 by way of grounded conductor 104, thereby starting the director to sending out the office code, as will be explained subsequently.

When the calling subscriber operates his calling device in accordance with the first digit 5 in the subscriber's number, five impulses of current are delivered to stepping magnet 445 of the digit register DR by way of a circuit previously traced to wiper 253 of the master digit control switch, and thence by way of the third associated bank contact and series relay 444. As a result, wiper 451 of the switch DR is advanced step by step until it comes into engagement with the fifth associated bank contact. Slow acting series relay 444 is maintained energized during the stepping movement of the switch and maintains conductor 357 disconnected at armature 449. At the end of the stepping movement, relay 444 deenergizes and places ground on conductor 357 at armature 449.

so as to allow the first digit in the subscriber's number to be sent out. This ground potential comes through off normal contacts 447 which became closed when the switch wiper moved from its normal position. At the end of the 5 series of impulses, the wipers of the master digit control switch MDC are advanced another step in the hereinbefore described manner, whereupon wiper 253 comes into engagement with the conductor leading to the stepping magnet of the digit register DR'.

The subscriber now calls the three remaining digits 6, 7, and 8 in the desired number, whereupon the digit register switches 10 DR'-DR³, inclusive, are operated to step their wipers around in accordance with the three remaining digits, respectively, the operation of each of these switches being the same as that of the digit register DR, previously described.

In response to the placing of ground upon start conductor 247 at the end of the calling of the second office digit, as explained hereinbefore, relay 375, Fig. 6, energizes and disconnects ground from the conductors extending to the contacts of the bank of wiper 352 of the sequence switch S at armatures 385-388, inclusive. As a further result of the placing of ground upon start conductor 247, the first four contacts in the bank of wiper 354 of the sequence switch S are grounded, whereupon a ground potential is extended from wiper 354 to wiper 351, by way of conductor 370, and thence by way of conductor 264 to the lower wiper 263 of the office register OR. Since wiper 263 is in engagement with the bank contact with which conductor 283 is connected, this ground potential extends by way of the associated IDF jumper to the seventh impulse conductor 297. From the seventh impulse conductor 297, this ground potential extends to conductor 367 by way of the resting contact of the upper armature of the seventh impulse counting relay 467, Fig. 7, and said armature. In response to the grounding of conductor 367, a circuit is closed for relay 380, Fig. 6, by way of the resting contact of armature 399 and said armature. Relay 380, upon energizing, closes a circuit for itself independent of armature 399 and its resting contact at armature 412; connects up sending relay 381 at armature 411; and at armature 410 opens a point in the circuit of stepping magnet 350 and closes 5 a circuit for slow acting relay 379. Relay 379, upon energizing, opens the initial circuit of relay 380 at armature 399, leaving relay 380 energized through armature 412 and its working contact; prepares a circuit for stepping magnet 350 at armature 398; and at armature 397 places ground on locking conductor 368. Relay 381, upon energizing the 10 first time ground is placed on conductor 371 by the rotary interrupter I after armature 411 is attracted, closes a circuit for the lower

winding of pick-up relay 382 at armature 413; and at armature 414 removes ground from the outgoing impulse conductor 248. This latter operation does not have any effect, however, owing to the fact that conductor 248 is at this time maintained grounded through armature 417 and its resting contact. Pick-up relay 382, which is of the same marginal two-step type as relay 201, Fig. 4, energizes over its lower winding just enough to operate the lightly adjusted armature 416, but not enough to operate the more stiffly adjusted armatures 415 and 417. When relay 381 deenergizes, it removes the shunt from around the upper winding of relay 382 at armature 413 and at armature 414 replaces ground on conductor 248. When this occurs, current flows through the two windings of relay 382 in series, whereupon the said relay energizes fully, thereby disconnecting armature 413 of sending relay 381 from its own windings and extending it by way of conductor 369 to armature 477 of the first impulse counting relay 461, Fig. 7. As a further result of the energization of relay 382, it disconnects ground from conductor 248 at armature 417, leaving the said conductor grounded only through armature 414 and its resting contact. The next time relay 381 energizes, it removes ground from conductor 248 at armature 414, thereby opening the circuit of repeating relay 127 of the repeater R', Fig. 3, and at armature 413 closes a circuit for the lower winding of the marginal two-step counting relay 461, whereupon relay 461 energizes part way and grounds its upper winding at armature 476. When relay 381 deenergizes again, it opens the initial circuit of relay 461 at armature 413 and at armature 414 replaces the ground potential on conductor 248. When this occurs, relay 461 energizes fully; disconnects the first impulse conductor 291 from conductor 367 at armature 475; and at armature 477 extends conductor 369 to the corresponding armature of counting relay 462. As a result of the ground potential being replaced on conductor 248, the repeating relay of the repeater R' energizes again. As sending relay 381 energizes and deenergizes, one of the impulse counting relays, Fig. 7, pulls part way up for each energization and all the way up for each de-energization thereof and, upon each energiza of relay 381, ground is removed from the outgoing impulse conductor 248 at armature 414. This continues in the manner described until the seventh impulse counting relay 467 pulls all the way up as it does upon the eighth deenergization of sending relay 381, at which time ground will have been removed from the outgoing impulse conductor 248 seven times. Relay 467, upon energizing fully, disconnects ground from conductor 367 at its upper armature, whereupon relay 380, Fig. 6, deenergizes; disconnects 15

impulse relay 381 at armature 411 while the latter relay is still deenergized; and at armature 410 opens the circuit of slow acting relay 379 and closes a circuit for stepping magnet 350 of the sender S by way of armature 398 and its working contact. Relay 379 is slow acting and is adjusted so as to hold up long enough to give the proper space between digits. Stepping magnet 350, of the sender 10 S, upon energizing, merely advances the associated pawl into engagement with the next notch in the ratchet wheel and does not move the wipers.

In the repeater R', Fig. 3, repeating relay 127, upon deenergizing in response to each of the seven interruptions produced in its circuit by sending relay 381 as described above, opens the circuit of line relay 163 of the selector D at armature 136. Each time line 20 relay 163 deenergizes, it closes the following circuit for vertical magnet 168: From ground by way of the resting contact of armature 182 and said armature, armature 174 and its resting contact, armature 176 and its working contact, series relay 165, and vertical magnet 168 to battery. By the operation of vertical magnet 168, the switch wipers 184-186, inclusive, are lifted step by step until they stand opposite the seventh level of bank 30 contacts. Slow acting series relay 165 is maintained energized in series with vertical magnet 168 during the entire vertical movement. Upon the energization of series relay 165 and the closure of off normal contacts 35 173, which occur on the first vertical step, a circuit is closed from release trunk conductor 161 through armature 177 and its working contact, off normal contacts 173, and interrupter contacts 171, for stepping relay 40 166. Stepping relay 166, upon energizing, closes a locking circuit for itself at armature 178 and at armature 179 prepares a circuit for rotary magnet 172.

At the end of the vertical movement, relay 45 165 deenergizes and completes the circuit of rotary magnet 172 at armature 177. Rotary magnet 172, upon energizing, advances the wipers 184-186, inclusive, into engagement with the first set of bank contacts in the seventh level, and near the end of its stroke, opens the circuit of stepping relay 166. Stepping relay 166, upon deenergizing, opens the circuit of rotary magnet 178 at armature 179, whereupon rotary magnet 172 deenergizes and closes its interrupter contacts again. In case the trunk terminating in the first set of bank contacts is idle, switching relay 167 energizes immediately. However, if the 50 trunk is busy, switching relay 167, being short circuited by the ground potential found on the test contact thereof by test wiper 185, does not energize. In this case, stepping magnet 166 energizes from ground on the busy test contact and again closes the circuit of rotary magnet 172 at armature 179, where-

upon the switch wipers are advanced into engagement with the second set of bank contacts. This alternate operation of stepping magnet 166 and rotary magnet 172 continues until an idle trunk is reached, whereupon 70 switching relay 167, being no longer short circuited, energizes in series with stepping relay 166, the latter relay not energizing at this time on account of the high resistance of switching relay 167. Switching relay 167, 75 upon energizing, disconnects ground from armature 174 of line relay 163 at armature 182, thereby opening the circuit of release relay 164; opens the test circuit and prepares the holding circuit at armature 181; and at 80 armatures 180 and 183 disconnects conductors 160 and 162 from the windings of line relay 165 and extends them by way of wipers 184 and 186 to the line relay of the trunk seized, whereupon the last named line relay and its 85 associated release relay energize and the latter places ground on the release trunk conductor of the trunk, thereby establishing the usual holding circuit for switching relay 167 before release relay 164 has had time to de- 90 energize.

At the end of the predetermined interval, relay 379 deenergizes; prepares a circuit for relay 380 at armature 399; removes ground from conductor 368 at armature 397, whereupon pick-up relay 382 and such counting relays in Fig. 7 as are energized, deenergize; and at armature 398 opens the circuit of stepping magnet 350. Stepping magnet 350 now deenergizes and advances the wipers 351-354, inclusive, of the sender S into engagement with the second set of bank contacts. Wiper 351, upon being advanced, disconnects the grounded conductor 370 from conductor 264 and connects it to conductor 265, thereby removing the ground from the lower or first digit wiper 263 of the office register OR and extending it to the second digit wiper 262. Since wiper 262 is in engagement with the bank contact with which conductor 282 is connected, and since conductor 282 is jumped to the second impulse conductor 292, ground is placed on the latter. This ground potential extends by way of conductor 292 and the resting contact of the upper armature of the second counting relay 462, Fig. 7, and said armature to conductor 367. In response to the ground potential being placed on conductor 367, relays 380 and 379 energize one after the other as in the preceding 110 case, and relay 381 begins to vibrate under the control of the interrupter I, each deenergization after the first resulting in the removal of the ground potential from the outgoing impulse conductor 248, pick-up relay 382 being operated upon the first energization of relay 381. Since the controlling ground potential is coming in through the upper armature of the second counting relay 462 at 120 this time, ground is removed from conductor 125 367. This continues until the second counting relay 462 has completed its cycle, whereupon the ground potential is again placed on conductor 367, the second counting relay 462 being deenergized and the first counting relay 461 being energized. This completes the cycle of the second counting relay 462. The first counting relay 461 continues to vibrate until the 130

367 upon the energization of the second counting relay 462, at which time the ground potential will have been removed from the outgoing impulse conductor 248 twice, therefore by sending out the second office digit 2.

The second digit of the office code is reported by relay 127 in the repeater R', Figure 3, the same as the first digit, and the second selector to which the connection has been extended by the first selector D is operated in the usual manner to trunk the call to the distant office in which the called line is located.

When ground is removed from conductor 367, relays 380 and 379 fall back one after the other in the order named, thereby sending an impulse of current to stepping magnet 350 of the sequence switch S upon the deenergization of relay 379, which causes the wipers of the sequence switch to be advanced into engagement with the third set of bank contacts. When this occurs, wiper 351 disconnects the grounded conductor 370 from conductor 265 and connects it to conductor 266, thereby grounding the third digit wiper 261 of the office register OR. Since wiper 261 is in engagement with conductor 281, and since conductor 281 is jumpered to the third digit skip conductor 305, there being no third digit in the office code, this ground potential is extended to conductor 305. When conductor 305 is grounded, stepping magnet 350 of the sequence switch S energizes through wiper 352, which is standing on the bank contact with which conductor 305 is

connected, and interrupts its own circuit at contacts 349, whereupon it immediately deenergizes and advances the wipers of the sequence switch into fourth position. When this occurs, wiper 351 disconnects the ground potential from conductor 256 and places it on conductor 267, thereby grounding the fourth digit wiper 260 of the office register OR. Since the office to which the call is going is an automatic office, conductor 280 is jumpered to conductor 302. Consequently, the ground

potential extends by way of conductor 280, the associated IDF jumper, conductor 302, normally closed contacts controlled by armature 392, and relay 377 to battery. Relay 377, upon energizing, locks itself to the grounded conductor 244 and opens its initial circuit at armature 392; places ground on the ninth position contact of sequence switch wiper 353 at armature 393, so as to operate the switch-through relay 376, Fig. 4, when sequence switch wiper 353 reaches the ninth position instead of the tenth position for which it is normally set; and places ground on conductor 306 at armature 391, thereby causing the sequence switch S to advance automatically from the fourth to the fifth position.

When the wipers of the sequence switch S reach the fifth position, wiper 354 encounters the conductor 357, which conductor is

grounded only in case the calling subscriber has called the first digit in the desired subscriber's number. Assuming the first digit 5 in the subscriber's number to have been dialled prior to this time, as explained hereinbefore, in which case conductor 357 is grounded, conductor 370 is grounded through wiper 354. Consequently, wiper 351, being in fifth position, places ground on wiper 451 of the digit register DR, Fig. 7, by way of conductor 356. Since wiper 451 has been advanced into engagement with the fifth associated bank contact in accordance with the first digit 5 in the desired subscriber's number, as hereinbefore explained, the above mentioned ground potential is extended to the fifth impulse conductor 295 and extends from thence to conductor 367 by way of the resting contact of the upper armature of the fifth counting relay 465 and said armature. In response to the ground potential being placed on conductor 367, the relay sender starts to operate in the previously described manner and since the ground potential is being supplied to conductor 367 by way of the fifth impulse conductor 295, five impulses are sent out at armature 414 at this time. At the end of the series of impulses, ground is removed from conductor 367, upon the energization of counting relay 465, whereupon relays 380 and 378 fall back one after the other in the usual manner, and the wipers of the sequence switch are advanced into the sixth position.

In the sixth position of the sequence switch S, starting ground is supplied to wiper 354 by the digit register DR' by way of conductor 359, and is extended by wiper 351 of the sequence switch to wiper 452 of the digit register DR' by way of conductor 358. Accordingly, the second digit 6 in the subscriber's number is sent out in the same manner as the first digit 5, after which the wipers of the sequence switch are advanced into seventh position.

In the seventh position of the sequence switch S, ground is supplied to wiper 354 by the digit register DR² by way of conductor 361, and in turn is supplied to wiper 453 of the digit register DR² by wiper 351 of the sequence switch S by way of conductor 360. Consequently, the third digit 7 in the subscriber's number is sent out in the usual manner, after which the wipers of the sequence switch are advanced into the eighth position.

Similarly, in the eighth position of the sequence switch S, ground is supplied to wiper 354 by the digit register DR³ by way of conductor 363, and in turn is supplied to the wiper 454 of the digit register DR³ by wiper 351 of the sequence switch by way of conductor 362. Consequently, the fourth digit 8 in the subscriber's number is sent out in the usual manner, at the end of which the wipers of the sequence switch are advanced into the

ninth position in the previously described manner.

Responsive to the transmission of the four digits in the subscriber's number, two selectors and a connector in the distant automatic office are operated in the usual manner to complete the connection to the called subscriber's line.

- When the wipers of the sequence switch 10 reach the ninth position, a circuit is closed for switch-through relay 376, Fig. 4, as follows: from ground by way of the working contact of armature 393 and said armature, ninth contact in the bank of sequence switch wiper 353 and said wiper, conductor 243, armature 222 and its resting contact, normally closed contacts controlled by armature 389, and switch-through relay 376 to battery. Relay 376, upon energizing, locks itself to conductor 102 and opens its initial circuit at armature 389, and at armature 390 disconnects the incoming impulse conductor 101 from relay 202 and connects it to ground instead. When this occurs, relay 126 in the repeater R' energizes over the following circuit: from ground by way of the working contact of armature 390 and said armature, conductor 101, wiper 148 of the secondary switch SS', working contact of armature 143 and said armature, armature 129 of line relay 125 and its working contact, and relay 126 to battery. Relay 126, upon energizing, locks itself to release trunk conductor 161 at armature 133; connects release trunk conductor 122 of the repeater R' with release conductor 161 of the selector S at armature 132; and connects the line conductors 121 and 123 of the repeater R' with line conductors 160 and 162 of the selector D at armatures 130 and 135. The adjustment of the contacts of relays 126 is such that armatures 131 and 134 break away from their resting contacts just after armatures 130 and 135 make contact, thereby disconnecting line relay 125. The last circuit change produced by relay 126 is that it disconnects the local bridge from across conductors 160 and 162 at normally closed contacts controlled by armatures 130 and 135, thereby leaving the established connection under the direct control of the calling substation. The resistance 152 is included in the local bridge for the purpose of preventing unduly loud clicks when the local bridge and the subscriber's loop are placed together and separated.
- 65 In the director, as a further result of the sequence switch S advancing to ninth position, wiper 354 engages conductor 365 which is the conductor that is grounded when the series relay of the fifth digit register DR⁴ comes to rest after the operation of the said switch DR⁴. In this case the digit register DR⁴ has not been operated, but conductor 365 is normally grounded through armature 394 of relay 378 and its resting contact, and the ground potential is extended through the ninth contact

tact of wiper 354 and said wiper, conductor 370, wiper 351, and conductor 364 to wiper 455 of the digit register DR⁴. Since wiper 455 of the digit register DR⁴ is not operated, the placing of ground thereon has no effect at this time. However, conductor 364 is normally connected to the first impulse conductor 291 by way of the resting contact of armature 396 of relay 378 and said armature. Consequently, this ground potential extends from conductor 291 to conductor 367 by way of the resting contact of armature 475 of the first counting relay 461, Fig. 7, and the relay sender starts to send out the digit 1. The operation of the sender at this time has no effect, however, for the reason that the switch-over occurs immediately upon the sequence switch being advanced to ninth position, as hereinbefore explained, and the control of the connection is removed from the outgoing repeating relay 127 in the repeater R' before the first impulse comes along.

In the repeater R', Fig. 3, line relay 125 deenergizes in response to being cut off by relay 132 at armatures 131 and 134, as pointed out abcve, and opens the initial circuit of relay 126 at armature 129, leaving relay 126 energized through its locking circuit which is closed at armature 133. As a further result of the deenergization of line relay 125, it opens the circuit of the slow acting line relay 137 of the secondary switch SS' at armature 128. Relay 137, upon deenergizing, opens the circuit of switching relay 138 at armature 140, whereupon switching relay 138 deenergizes and disconnects wipers 148—151, inclusive. By this operation, the ground potential is removed from conductor 104 of the director trunk, whereupon relay 208, Fig. 4, deenergizes but does not perform any particular function at this time. As a further result of the removal of the ground potential from conductor 104, the ground potential is removed from starting conductor 247, whereupon relay 375, Fig. 6, deenergizes and grounds all the contacts in the bank of wiper 352 of the sequence switch S. When this occurs, the wipers of the sequence switch are automatically advanced through its remaining positions and into the first position by the buzzer like action of the stepping magnet 350. When ground is removed from conductor 102 of the director trunk, relays 376, 204, and 205, Fig. 4, deenergize, and relay 204 places ground on release conductor 242 at armature 216, whereupon the office register OR and the switch MDC are released in the usual manner. Conductor 242, it will be noted, is extended across the top of Fig. 7 and a lead is taken from the said conductor to the lower off normal contacts of each of the digit registers DR-DR⁴, inclusive. Accordingly, the release magnets of such digit registers as are off normal energize and restore the digit reg-

isters to normal position, the release magnet 446 of the digit register DR, for example, is energized through off normal contacts 448, and the circuit of release magnet 446 is opened at off normal contacts 448 when the wiper 451 reaches normal position. The director is now in condition to be seized and to handle the next call.

Regarding the established connection, it may be said that the connection is released upon the handing up of the subscriber at substation A' by the removal of the ground potential from the release trunk conductor by the switch to which connection has been extended. When this occurs, the switching relay 167 of the selector D, relay 126 of the repeater R', and switching relay 110 of the line switch C' deenergize. The deenergization of relays 110 and 126 restores conditions in the line switch C' and the repeater R' to normal and the deenergization of switching relay 167 of the selector D results in a circuit being closed for release magnet 169, which circuit includes armatures 182, 174, and 176, and off normal contacts 170. The selector D is restored to normal position in the usual manner upon the energization of release magnet 167, the circuit of release magnet 167 being opened at off normal contacts 170 by the switch shaft when the latter reaches normal position.

It will be assumed now that the subscriber at substation A' desires to converse with a subscriber whose line terminates in the manual party line office 92, whose line number is 1234, and whose station number is 5. It will be assumed further that, when the subscriber removes his receiver, his individual line switch C selects the trunk leading to the repeater R', and that the secondary switch SS' selects the director trunk comprising conductors 101-104, inclusive, and also that the subscriber has dialled the first digit 9 in the number of the desired office with the hereinbefore described results.

In response to the calling of the second office digit 2, the wipers 260-263, inclusive, of the office register OR are advanced into engagement with the second set of bank contacts in the ninth level. By the operation of rotary magnet 251 of the master digit control switch MDC, the wipers thereof are advanced another step, whereupon the operating circuit is extended to stepping magnet 445 of the digit register DR by wiper 253. At the same time, ground is placed on start conductor 247 by wiper 254, whereupon the relay sender begins to send out the office code.

The calling subscriber now operates his calling device in accordance with the digits 1-5, inclusive, whereupon the digit registers DR-DR⁴, inclusive, respond in the usual manner to register the digits called, the necessary control being exercised by the master

digit controller MDC as hereinbefore explained.

When the ground potential is placed on the start conductor 247 as pointed out above, ground is extended through the first contact 70 in the bank of wiper 354 of the sequence switch S to conductor 370, and thence by way of wiper 351 of the sequence switch S, and conductor 264 to the first digit wiper 263 of the office register OR. From an inspection of the drawings, it will become apparent that the first three contacts from the bottom of the set with which the wipers of the office register are now in engagement, or the contacts in which the conductors 80 277-279, inclusive, are terminated, are jumpered so as to send out the office code 850. Consequently, the ground potential on wiper 263 is extended over conductor 279 and the associated IDF jumper, to the eighth impulse 85 conductor 298. That being the case, the relay sender operates in the previously described manner to send out the first digit 8 in the office code, after which an impulse of current is delivered to stepping magnet 350 of 90 switch S, whereupon the wipers are advanced into second position and ground is placed on the second digit wiper 262 of the office register OR. This ground potential extends by way of bank conductor 278 and the associated 95 IDF jumper to the fifth impulse conductor 295. Consequently, the second digit 5 in the office code is sent out by the relay sender, after which the sequence switch S is advanced into 100 third position and the ground potential is extended over the third digit wiper 261, the bank contact with which it is in engagement conductor 277, and the associated IDF jumper to the tenth impulse conductor 300, whereupon the third digit 0 in the office code is 105 sent out.

Responsive to the transmission of the three office digits, the call is trunked through the automatic network to the desired manual office, where call indicating apparatus is prepared for the reception of the digits in the called subscriber's number.

When the wipers of the switch S are advanced into fourth position after the sending out of the third digit in the office code, 115 ground is placed on the fourth wiper of the office register OR, and is extended from thence by way of the bank contact with which it is in engagement, conductor 276, the associated IDF jumper, ring digit conductor 303, the normally closed contacts controlled by armature 395 of relay 378, and relay 378 to battery. Relay 378, upon energizing, closes a locking circuit for itself and opens its initial circuit at armature 395; disconnects ground from conductor 365 at armature 394 so as to cause the sender to wait for the operation of the fifth digit register DR⁴; disconnects the first impulse conductor 291 from conductor 364 at armature 396, so as to leave 125 130

- the sender free to send out the digit set up on the digit register DR⁴; and at armature 394 places ground on conductor 306, thereby causing the switch S to advance automatically from its fourth to its fifth position.
- The sender now sends out the digits set up on the digit registers DR-DR⁴, inclusive, in the hereinbefore described manner, the sequence switch S being advanced automatically in the usual manner at the end of each digit. It will be noted that since relay 377 is not energized at this time, ground is not placed on conductor 243 of wiper 353 of the sequence switch S until the sequence switch is advanced into its tenth position. Consequently, the director does not switch through until the fifth or party selecting digit has been sent out and the sequence switch has been advanced to tenth position.
- 20 The five digits in the called number are registered by the call indicator in use at the manual office and at the proper time are displayed to an operator, who completes the connection in the usual manner.
- 25 When the sequence switch reaches tenth position, conductor 243 is grounded, whereupon the director switches through in the hereinbefore described manner.
- It will be assumed now that the subscriber at substation A' desires to converse with a subscriber in the individual line manual office 93, whose number is 1234. It will be assumed further that when the subscriber removes his receiver, the individual line switch C' selects the trunk extending to the repeater R', and that the secondary switch SS' selects the director trunk comprising conductors 101-104, inclusive. That being the case, the office register OR is raised to the ninth level in response to the dialling of the first office digit 9, and is rotated three steps in response to the dialling of the second digit 3, and the digit registers DR-DR⁴, inclusive, are operated in response to the next four digits dialled and register such digits.
- The sender starts to send out the office code at the end of the dialling of the second office digit in the usual manner. It is assumed that the office code desired in the present case is 859. Accordingly, the conductors 275, 274, and 273 of the ninety-third set of bank contacts of the office register OR are jumpered to the eighth, fifth, and ninth impulses conductors, respectively. Since the office to which the call is going is an individual line manual office, no special relay need be pulled up, and the fourth conductor 272 of the set is jumpered to the fourth digit skip conductor 306. When the fourth digit wiper 260 of the office register OR is grounded by the sequence switch S after the sending out of the third digit 9 in the office code, ground is extended by way of conductor 272 and the associated IDF jumpered to the fourth digit skip conductor 306, whereupon the wipers of the sender are advanced automatically into the fifth position.
- The sender now sends out the digits 1-4, inclusive, of the subscriber's number in the usual manner, the sequence switch S being advanced one step after each digit.
- When the sequence switch S reaches the ninth position, ground is supplied to conductor 370 by way of armature 394 of relay 378 and its resting contact, ninth contact in the bank of wiper 354, and wiper 354. This ground potential is extended by wiper 351 to conductor 364 and extends from thence to the first impulse conductor 291 by way of the resting contact of armature 396 and said armature. Consequently, the relay sender proceeds to send out the digit 1, this digit being added automatically by the director in order to switch the call indicator at the manual office into displaying position for reasons hereinbefore given. As soon as the digit 1 has been sent out, the sequence switch S is advanced into tenth position, whereupon ground is placed upon conductor 243 by way of wiper 353, and the director switches thru as a result.
- In order to explain the operation of the director in calling the long distance operator, it will be assumed that the subscriber at substation A desires to call the long distance operator. It will be assumed further, that the connection is extended upon the removal of the receiver at substation A' to the director trunk which comprises conductors 101-104, inclusive of the secondary switch SS'.
- When the calling subscriber operates his calling device in accordance with the digit 0, which digit is the one assigned to the long distance operator, the office register OR, Fig. 5, raises its wipers opposite the tenth level of bank contacts, which is the level in which the upper set of contacts shown in Fig. 5 is located. It will be remembered that relays 202 and 203, Fig. 4, are energized during the vertical movement of office register OR. Also, when the tenth level is reached, the switch shaft operates the tenth level springs 233-235, inclusive. Spring 233, upon being operated, disconnects the rotary magnet operating lead 246, so as to remove the rotary movement of the switch from under the control of the calling subscriber. Spring 235, upon coming into engagement with its associated contact, places ground upon the second contact in the bank of wiper 254 of the master digit control switch MDC, so as to cause wiper 254 to ground start conductor 247 when the master digit control switch is advanced to second position instead of the third as in other cases. The tenth level spring 234, upon being operated, prepares a circuit for rotary magnet 230. Relay 202, upon falling back at the end of the ventrical movement, opens the circuit of slow acting relay 203 at armature 212, at the same time closing 130

the usual circuit for stepping magnet 251 of the switch MDC. A branch of this circuit extends by way of the working contact of armature 213 and the said armature, conductor 238, spring 234 and its upper contact, and rotary magnet 230 to battery. Stepping magnet 250 of the master digit control switch MDC, upon energizing, advances wipers 253 and 254 into engagement with the second set of bank contacts and rotary magnet 230 of the office register OR, upon energizing, advances wipers 260-263, inclusive, into engagement with the first set of bank contacts in the tenth level, which is the set of contacts in which conductors 268-271, inclusive, terminate. After an interval, slow acting relay 203 falls back and opens the circuits of magnets 230 and 251 at armatures 213 and 214, respectively.

When wiper 254 is moved into engagement with its second bank contact, as described above, it places ground on start conductor 247, conductor 239 having been grounded by tenth level spring 233. Consequently, the relay sender starts to send out the code necessary to trunk the call to the long distance operator. The code in this case is assumed to be 46. Accordingly, conductor 271, Fig. 5, is jumpered to the fourth impulse conductor 294 and conductor 270 is jumpered to the sixth impulse conductor 296.

In order to cause the director to switch thru after the calling of the second digit 6 in the code, conductor 269 is jumpered to the code-number switch conductor 301. That being the case, when the third digit wiper 261 of the office register OR is grounded by wiper 351 of the sequence switch S, Fig. 6, after the second digit 6 is sent out, the ground potential extends by way of conductor 269, the associated IDF jumper, code-number switch conductor 301, and the third contact in the bank of sequence switch wiper 353, to switch conductor 243. Consequently, the director switches 45 through in the hereinbefore described manner.

The operation of the improved director when used by a paystation subscriber will now be considered. For this purpose, it will be assumed that the subscriber at substation A desires to make a call. The substation A, as before explained, is of the paystation type and the subscriber therat is instructed to deposit a coin before dialling. When the receiver is removed, a bridge is placed across line conductors 5 and 6, whereupon line relay 6 of the line switch C energizes and closes the usual circuits at armatures 13 and 14, whereupon the line switch C selects an idle trunk, which 55 trunk, it will be assumed, is the one comprising the conductors 18-20, inclusive. Switching relay 7 energizes when an idle trunk is reached or immediately upon the energization of line relay 8, in case the wipers 60 15-17, inclusive, are standing on an idle trunk

when the call is initiated, and at armatures 10-12, inclusive, switches the connection through to the trunk comprising conductors 15-20, inclusive. There is a bridge across conductors 18 and 20 of repeater R, conductor 70 20 being grounded through armature 47 and its resting contact, lower left hand winding of the repeating coil, and the lower winding of differential relay 32, and conductor 18 being connected to battery by way of armature 44 75 and its resting contact, upper left hand winding of the repeating coil, upper winding of differential relay 32, and line relay 35. Consequently, line relay 35 energizes. Differential relay 32, however, does not energize 80 until the circuit has been unbalanced by the depositing of a coin at the substation. Line relay 35, upon energizing closes a circuit for release relay 34 at armature 60. Release relay 34, upon energizing, prepares a circuit for relay 85 35 at armature 57, and at armature 58 places ground on conductor 78, thereby grounding release trunk conductor 19 by way of the normally closed contacts controlled by armature 64, so as to establish the usual holding circuit 90 for the line switch C. It will be noted that a circuit is closed for the lower winding of the electro polarized relay 31 from release trunk conductor 19. Relay 31, however, is marginally adjusted and does not energize at this time 95 on account of the resistance 50. As a further result of the energization of release relay 34, it closes a circuit for line relay 85 of the secondary switch SS at armature 56. Line relay 85, upon energizing, disconnects release trunk 100 conductor 76 of the associated selector from release conductor 19 of the repeater R at armature 88; closes a circuit for switching relay 86 and stepping magnet 93 in series at armature 87 closes the usual test circuit. The secondary switch SS now selects an idle trunk in the usual manner, which trunk, it will be assumed, is the one comprising conductors 101-104, inclusive. Switching relay 86, upon energizing when the idle trunk is found, 105 opens the test circuit and grounds wiper 95 at armature 90, and at armatures 89, 91, and 92 connects up the wipers 94, 96, and 97, respectively. When this occurs, repeating relay 37 energizes from ground on the outgoing impulse lead 103 of the trunk, through wiper 96 and armature 91 and its working contact, and at armature 67 closes a bridge across the conductors 75 and 77 leading to the associated first selector, whereupon the said selector is prepared for operation in the usual manner and release trunk conductor 76 is grounded. As a result of the ground potential being placed on wiper 95 of the secondary switch SS by armature 90, relay 204 in the 110 director, Fig. 4, energizes with the hereinbefore described results. The calling subscriber now hears the tone produced by the trunk tone apparatus TT, Fig. 5, and knows that he may start to dial the desired num- 115 120 125 130

- ber. This tone, it may be pointed out, comes into the repeater R over the impulse conductor 101 as is the case when the subscriber at substation A' is calling, and passes through the small tone condenser in the repeater R and the resting contact of armature 61 and said armature to the right hand windings of the repeating coil, and passes to ground by way of armature 66 and its resting contact.
- 10 In case the calling subscriber does nothing further, the timing mechanism in the director operates at the end of the prescribed time limit, and switches the call through to the first selector as hereinbefore described.
- 15 In case the subscriber desires to call the long distance operator, it is not necessary for him to cause the conductor 104 to be grounded by depositing a coin, for the reason that starting ground is supplied to wiper 254 of the master digit control switch MDC by way of conductor 239, as hereinbefore explained. It is necessary for the subscriber to ground conductor 104 by depositing a coin, however, before he can call any other subscriber. In order to explain how a paystation subscriber is prevented from establishing regular connections without depositing a coin, it will be assumed that he does not deposit a coin and that he operates his calling device in accordance with the first digit of the desired number, which digit will be some digit other than C.
- 20 When the calling device at substation A is turned for the first digit of the desired number, the circuit of line relay 35 of the repeater R is opened the desired number of times. Each time the line relay 35 deenergizes it closes a circuit for slow acting relay 33 by way of armature 57 and its working contact at armature 60. Relay 33, upon energizing, closes a locking circuit for itself at armature 52, which locking circuit includes armature 45 and its resting contact; prepares a circuit for slow acting relay 30 at armature 55, and at armatures 53 and 54 shunts the upper and lower windings of the differential relay 32 so as to improve the dialling circuit.
- 25 As a further result of each deenergization of line relay 35, the director impulse conductor 101 is grounded at armature 59, through the working contact of armature 59 of the secondary switch SS and said armature, and wiper 94. Consequently, a series of impulses representing the digit dialled is delivered by way of the previously traced circuit to vertical magnet 229 of the office register OR, and the wipers 260-263, inclusive, are raised opposite the desired level of bank contacts in the usual manner. It will be remembered that relays 202 and 203, Fig. 4, are maintained energized during the vertical movement of the office register OR. At the end of the vertical movement, relay 202 deenergizes and closes the usual circuit for stepping magnet 251 of the switch MDC at armature 212.
- 30 Also, since the tenth level shaft springs have not been operated, and since relay 208 has not been energized by the deposit of a coin at the calling substation, the following circuit is closed for relay 206. From ground by way of armature 212 of relay 202 and its resting contact, working contact of armature 213 and said armature, conductor 238, tenth level shaft spring 234, conductor 237, resting contact of armature 227 and said armature, and relay 206 to battery. Relay 206, upon energizing, closes a circuit for relays 207 and 256, Figs. 4 and 5, respectively, in series at armature 224. Relay 207, upon energizing, prepares the starting circuit at armature 226 and at armature 225 closes a locking circuit for itself and relay 256. Relay 256, upon energizing, connects up the special conductors 284-287, inclusive, to the office register wiper conductors 264-267, inclusive, respectively. As a further result of the energization of relay 206, it opens the outgoing repeating circuit at armature 220, whereupon repeating relay 237 in the repeater R deenergizes and opens the bridge across conductors 75 and 77 so as to release any partly established connection. As a still further result of the energization of relay 206, it places ground on release conductor 242 at armature 221, whereupon release magnet 231 of the office register OR energizes and restores the switch to normal.
- 35 After an interval, relay 203 deenergizes; opens the circuit of stepping magnet 251 of the switch MDC at armature 214; and at armature 213 opens the circuit of relay 206. Relay 206, upon deenergizing, places ground on starting conductor 247 at armature 224 by way of armature 226 and its working contact, and at armature 220 again closes the outgoing repeating circuit. Relay 203, it may be stated, is adjusted so as to be slightly slower in falling back than the ordinary release relay so as to insure that relay 206 remains energized long enough to release any partly established connection, which is necessary in case relay 206 is operated to trunk the call to a monitoring operator when the subscriber does not dial fast enough as hereinbefore pointed out. When ground is placed on start conductor 247, as pointed out above, the sender starts to send out the first digit in the desired code in the usual manner. From inspection of the drawings, it may be seen that the first digit conductor 284 is jumpered to the third impulse conductor 293, and that the second and third digit conductors 285 and 286, respectively, are both jumpered to the first impulse conductor 291. Consequently, the code sent out is 311.
- 40 In order to cause the director to switch thru at the end of the code, the fourth digit conductor 287 is jumpered to the code-number switch conductor 301. Consequently, the director switches through in the hereinbefore described manner when contact 287 is

grounded by the sequence switch S after the sending out of the third digit 1.

It will be assumed now that the subscriber at substation A has removed his receiver with the results hereinbefore described, and that he deposits the proper coin before turning his calling device. When the coin is deposited at substation A, it rolls down the chute and releases the trigger 4, whereupon the spring 2 is brought into engagement with its associated contact and connects up the polarized magnet 3. When this is done, the circuit is unbalanced sufficiently to allow the differential relay 32 in the repeater R to energize. The polarized magnet 3 at substation A, however, does not energize at this time on account of the small amount of current which flows through it. Differential relay 32 in the repeater R, upon energizing, closes a circuit for relay 38 as follows: from ground by way of armature 58 and its working contact, working contact of armature 51 and said armature, and relay 38 to battery. Relay 38, upon energizing, locks itself through armature 46 of relay 30 and its resting contact at armature 72, opens a point in the circuit of relay 39 at armature 71; prepares a circuit for relay 48 at armature 69; and at armature 68 grounds conductor 104 through the working contact of armature 92 and said armature and wiper 97 of the secondary switch SS. When this is done, the last eight contacts in the bank of wiper 254 of the master digit control switch MDC are grounded and relay 208 is energized.

The calling subscriber may now dial the desired number in the usual manner, whereupon the director operates in the previously described manner and routes the call to the desired line just as though the subscriber at substation A' were calling.

When conductor 101 is grounded in the director to switch the connection through after the director has sent out the last digit, a circuit is closed through wiper 94, armature 69 and armature 59, for switching relay 36. Switching relay 36, upon energizing, prepares a circuit for relay 39 at armature 65; locks itself to release trunk conductor 76 at armature 63; opens the circuit of line relay 85 of the secondary switch SS at armature 62; and at armatures 61 and 66 disconnects the talking conductors from the tone condenser and from ground and extends them through to conductors 75 and 77, at the same time disconnecting the local bridge from across conductors 75 and 77. The connection is now held up through the right hand repeating coil winding and through the upper winding of the marginally adjusted electro polarized relay 31. Relay 31 is not energized at this time, however, for the reason that current flowing through its upper winding opposes the current flowing through the lower

winding. The director is freed in the usual manner when relays 85 and 86 fall back.

When the calling subscriber answers, the current flow in conductors 75 and 77 is reversed in known manner, whereupon relay 51 energizes; short circuits resistance 50 at armature 49 so as to hold the relay energized regardless of current flow in the upper winding, and at armature 48 disconnects relay 40 from the negative high voltage battery and connects it to positive high voltage battery.

When the conversation is terminated, the two subscribers replace their receivers. When the receiver is replaced at substation A, the circuit of line relay 35 of the repeater R is opened. Line relay 35, upon deenergizing, opens the circuit of release relay 34 at armature 60. Release relay 34, upon deenergizing, opens the bridge across conductors 75 and 77 at armature 70, and at armature 58 closes a circuit for relay 30 by way of armature 55. Relay 30, upon energizing, opens the circuit of slow acting relay 33 at armature 45. Slow acting relay 33, however, retains its armature attracted for an interval. Also, relay 30 opens the circuit of slow acting relay 38, and places a multiple ground on release trunk conductor 19 at armature 46 before the holding ground has been removed by the connector. As a further result of the energization of relay 30, it disconnects line conductors 18 and 20 from the repeating coil windings at armatures 44 and 47 and connects them to the high voltage positive battery through relay 40, working contact of armature 69 and said armature, and armature 48 and its working contact. When this occurs, the polarized magnet at the substation energizes in the proper direction to collect the deposited coin, and relay 40 in the repeater R energizes and closes a circuit for relay 33 at armature 74 before the said relay 33 has deenergized. A moment later, relay 38 deenergizes; disconnects battery from conductors 18 and 20 at armature 71 connects up the common interrupter lead to relay 39. Relay 39 now begins to energize and deenergize quickly under the control of the common interrupter, and, upon each energization, momentarily applies battery to the line of substation A through relay 40. Consequently, relay 40 as well as the magnet at the substation is energized upon each energization of relay 39. Relay 40 maintains relay 33 energized by momentarily closing its circuit upon each energization at armature 74.

As soon as the coin at the substation passes into the coin box, or as soon thereafter as relay 33 is deenergized, the armature of magnet 3 returns to normal position and disconnects the magnet 3 from the line at spring 2. When this occurs, relay 40 in repeater R ceases to vibrate and relay 33 deenergizes. Upon deenergizing, relay 33 opens the circuit of relay 30 at armature 55. Relay 30,

upon deenergizing, removes ground from release trunk conductor 19 at armature 46, whereupon the various locked up relays of the repeater R deenergize and the connection 5 releases in the usual manner.

In case the subscriber makes a call and the called subscriber does not answer, relay 31 of the repeater R is not energized and when the receiver is replaced negative battery is 10 sent to the substation instead of positive battery and the coin is refunded.

Referring now to the off normal springs of the office register OR, Fig. 5, these springs are adjusted, as pointed out hereinbefore, so 15 that the normally open contacts are closed when the shaft of the switch is raised from its normal position, and so that spring 232 does not break away from its associated lower contact and come into engagement with its upper 20 contact until the second level of bank contacts is reached. Consequently, in case the calling subscriber, in removing the receiver, opens the line momentarily by accidentally striking the receiver against the switch hook after his 25 line circuit has been closed and the director selected, which is equivalent of dialling 1, the switch wipers are raised opposite the first level of bank contacts and relay 202, upon deenergizing, subsequently, closes a circuit 30 for release magnet 231 at armature 212. This circuit includes conductor 241, off normal spring 232 and its associated contact, and the normally open contacts controlled by spring 232. When this occurs, release magnet 35 231 energizes and restores the switch wipers to normal position. It may be pointed out that the wipers of the master digit controller MDC are not operated at this time, it being necessary for the shaft of the switch 40 OR to be raised two steps before spring 232 closes a circuit for magnet 251.

What is claimed is:

1. In a telephone system, a paystation line, a director adapted to be taken for use responsive to a call on said line, means in said director controlled from said line for registering the desired telephone number, means in said director for retransmitting said telephone number, and circuit arrangements such that the last named means is inoperative to retransmit any of said telephone number unless the calling subscriber has charged himself with the call.
2. In a telephone system, a paystation line, another line, a director adapted to be taken for use responsive to a call on either of said lines, mechanism in said director controlled from the calling line for registering the called 55 telephone number, means in said director for retransmitting said number, circuit arrangements such that the last named means is operative only in case the calling subscriber has charged himself with the call if the call 60 is from said paystation line, said last named

means being operative automatically in case the calling line is said other line.

3. In a telephone system as claimed in claim 2, means operative responsive to the calling of the first digit from a paystation line for routing the call to an operator's position by sending out a special number automatically in case the calling subscriber has not charged himself with the call. 70

4. In a telephone system, a paystation line, 75 automatic switching apparatus for extending said line when it is a calling line, a paystation repeater between said line and said switching apparatus, a register sender, and connections between said register sender and 80 said paystation repeater whereby said register sender is operated over the calling paystation line and whereby said switching mechanism is operated by said register sender. 85

5. In a telephone system, a paystation line, 90 automatic switching apparatus for extending said line when it is a calling line, a paystation repeater between said line and said switching apparatus, a register sender, connections between said register sender and said 95 paystation repeater whereby said register sender is operated over the calling paystation line, and means controlled jointly in accordance with the destination of the call and by the condition of the calling line for permitting the register sender to operate as specified or for preventing such operation. 100

6. In a telephone system, a calling line, a trunk line, means for connecting said lines together, a register sender arranged to be set 105 over said trunk line from said calling line, automatic switching mechanism controlled by said register sender in accordance with its set position to extend said trunk line, and circuit connections in said trunk line for supplying talking current to the calling line, said circuit connections being effective while the register sender is being set for supplying control current to the calling line to enable the setting of the register sender to be controlled 110 thereafter. 115

7. In a telephone system wherein calls from an automatic pay-station line are set up by step-by-step automatic switches controlled by a register sender set under the control of 115 said line, means in said register sender whereby calls from said line are normally barred, and means responsive to a particular setting of the register sender for disabling the barring means. 120

8. In a telephone system wherein calls from an automatic pay-station line are set up by step-by-step automatic switches controlled by a register sender set under the control of said line, means in said register sender whereby calls from said line are normally barred, and means responsive to the action of a pay-station subscriber on said pay-station line charging himself with a call for removing said bar. 125 130

9. In a telephone system wherein calls from an automatic pay-station line are set up by step-by-step automatic switches controlled by a register sender set under the control of said line, means in said register sender whereby calls from said pay-station line are normally barred, and means for disabling said bar responsive either to the act of a subscriber on said pay-station line charging himself with a call or to the register sender being set into a predetermined position.

10. In a telephone system wherein calls from pay-station lines are set up through automatic switches under the control of register senders which are in turn set over such lines, pay station devices on said lines, means whereby the senders refuse to operate any of the automatic switches to set up connections desired by pay-station subscribers unless the subscriber making a call has charged himself with such call.

11. In a telephone system wherein automatic switches are operated under the control of register senders to set up connections from calling lines to called lines in accordance with the position in which the register senders are set over calling lines, the calling lines being of two classes, the called lines also being of two classes, and discriminating means whereby the register senders are enabled to set up connections to called lines of both classes if the call is from a calling line of one class and are enabled to set up connections to called lines of only one class if the call is from a calling line of the other class.

12. In a telephone system wherein automatic switches are operated under the control of register senders to set up connections from calling lines to called lines in accordance with the position in which the register senders are set over the calling lines, said calling lines being of two classes, the called lines also being of two classes, restricting means whereby the register senders are enabled to set up connections to lines of both classes if the call is from a calling line of one class and are enabled to set up connections to lines of only one class if the call is from a calling line of the other class, and means whereby a subscriber on a calling line of the said other class may remove the restriction against his line by assessing a charge against himself.

13. In a telephone system, a calling line, a trunk line, means for connecting said lines together, a register sender arranged to be set over said trunk line from said calling line, automatic switching mechanism controlled by said register sender to extend said trunk line, and circuit connections in said trunk line for supplying transmitter current to the calling line throughout the entire time that the calling line and trunk line are connected together.

14. In a telephone system, a calling line, a trunk line, means for connecting said lines

together, a register sender arranged to be set over said trunk line from said calling line, automatic switching mechanism controlled by said register sender to extend said trunk line, a repeating coil and a line relay in said trunk line, and circuit connections including said line relay and repeating coil for supplying talking current to the calling line while the connection is being set up and during conversation. 75

15. In a telephone system, a calling line, a trunk line, means for connecting said lines together, a register sender arranged to be set over said trunk line from said calling line, automatic switching mechanism controlled by 80 said register sender to extend said trunk line, means including a line relay in said trunk line and controlled over the calling line to effect the said setting of the register sender, and circuit connections for supplying talking current to the calling line during conversation through said line relay. 85

16. In a telephone system, a calling line, a trunk line, means for connecting said lines together, a register sender arranged to be set 90 over said trunk line from said calling line, automatic step-by-step switches controlled by said register sender in accordance with its set position to extend said trunk line, and circuit connections in said trunk line for 95 supplying talking current to the calling line during conversation.

17. In a telephone system, a calling line, a trunk line, means for connecting said lines together, a register sender arranged to be set 100 over said trunk line from the calling line, automatic switching mechanism controlled by said register sender by trains of impulses to extend said trunk line in accordance with the set position of the register sender, and circuit 105 connections in said trunk line for supplying transmitter current to the calling line during conversation.

18. In a telephone system, two classes of lines, automatic switching apparatus, a register sender arranged to be set over a line of either class to extend the connection from such line by operating said automatic switching apparatus, and means associated with said register sender for causing it to exert a different controlling influence upon the automatic switching apparatus depending upon the class of the calling line. 110 115

19. In a telephone system wherein register senders are set over subscribers' lines and control automatic switching apparatus to extend connections from such lines, said lines being of two classes, means for causing said register sender to respond differently to a setting depending upon the class of the line from which it is set. 120 125

20. In a telephone system wherein register senders are set over paystation lines in accordance with desired numbers to control automatic switching apparatus to extend said 130

lines, means for preventing the register senders from recording a desired number unless the calling paystation subscriber has charged himself with the call.

- 5 21. In a telephone system, a paystation line, a register sender arranged to be taken for use responsive to a call on said line, means in said register sender controlled from said line by impulses for registering the desired 10 telephone number and for retransmitting said telephone number, and circuit arrangements such that said means is inoperative unless the calling subscriber has charged himself with the call before the transmission of 15 said impulses is completed.
22. In a telephone system, a paystation line, a register sender arranged to be taken for use responsive to a call on said line, means in said register sender controlled from said 20 line registering the desired telephone number and for retransmitting said telephone number, and circuit arrangements such that said means is inoperative unless the calling subscriber has charged himself with the call prior 25 to said registration.

23. In a telephone system wherein calls from paystation lines are set up over trunk lines under the control of register senders common to said trunk lines and which are in 30 turn set over said trunk line, paystation devices on said paystation lines, a testing device in each of said trunk lines controlled from the calling line in accordance with whether the calling subscriber has charged 35 himself with the call or not, and means controlled by said device for determining whether the register sender shall operate to control the automatic switches to set up the connection or not.

- 40 24. In a telephone system wherein calls from paystation lines are set up over trunk lines under the control of register senders common to said trunk lines and which are in turn set over said trunk line, paystation devices on said paystation lines, a testing device in each of said trunk lines controlled from the calling line in accordance with whether the calling subscriber has charged 45 himself with the call or not, and means controlled by said device for determining whether the register sender shall register the number or not.

- 55 25. In a telephone system wherein automatic switching apparatus is operated over trunk lines by register senders common to such trunk lines to extend connections from paystation lines, and means in such trunk lines controlled from the paystation line for determining whether the register senders 60 shall operate the automatic switching apparatus to set up a desired connection or not in accordance with whether the paystation subscriber has charged himself with the call or not.

- 65 26. In a telephone system wherein connec-

tions from paystation lines are set up over trunk lines by automatic switching apparatus and under the control of register senders and only in case the calling paystation subscribers have charged themselves with the 70 calls, said register senders being common to said trunk lines, charge testing means in said trunk lines controlled over the calling paystation lines to determine whether the register senders shall operate or not.

75 27. In a telephone system, a plurality of paystation lines, a plurality of trunk lines, means responsive to the initiation of a call on a paystation line for connecting an idle one of said trunk lines to the calling paystation line and to an idle one of said register senders, a testing device in the last named trunk line, means for operating said testing device only in case the calling paystation subscriber has charged himself for the call he is about to make, and means for preventing said register sender from operating to perform the functions set forth unless said testing device in the trunk line has operated.

80 28. In a telephone system wherein calls from paystation lines are set up under the control of register senders which are in turn set over such lines, paystation devices on said lines, means whereby a plurality of the automatic switches necessary to complete a desired connection are left unoperated unless the subscriber making a call has charged 85 himself with such call.

85 29. In a telephone system wherein automatic switching apparatus is operated by impulses transmitted by register senders which are in turn positioned over paystation lines, means in said register senders whereby calls from said paystation lines are normally barred, and means responsive to the action of the paystation subscriber on said paystation line charging himself with a call for removing 90 said bar.

95 30. In a telephone system wherein calls from paystation lines are set up by automatic switches controlled by register senders set under the control of said lines, means in said register senders for registering and retransmitting desired numbers in case the paystation subscribers charge themselves with the calls, and means for trunking any call over a route different from the one over which it would be trunked otherwise in case the calling paystation subscriber fails to charge 105 himself with the call.

110 31. In a telephone system wherein calls from paystation lines are set up by automatic switches controlled by register senders set under the control of said lines, means in said register senders for registering and retransmitting desired numbers in case the paystation subscribers charge themselves with the calls, a special monitoring position, and means for trunking any call to said monitoring position in case the calling paystation 115 120 125 130

- subscriber has failed to charge himself with a call.
32. In a telephone system wherein calls from paystation lines are set up by automatic switches controlled by register senders set under the control of said lines, means in said register senders for registering and retransmitting desired numbers in case the paystation subscribers charge themselves with the calls, and means for causing said register sender to retransmit a special number in case the calling paystation subscriber has not charged himself with a call. 70
33. In a telephone system wherein connections from calling lines are set up through automatic switches by register senders which are set over said calling lines, called lines of two classes, certain of said calling lines being restricted to calls to called lines of one class only, and means in said register senders for sending out a special number in case a restricted line attempts to call a line of the other of said classes. 80
34. In a telephone system, calling lines arranged in groups according to the class of service to which they are entitled, link circuits individual to each group, control devices common to all groups, said control devices being associated with calling lines through the intermediation of said link circuits, and means in said link circuits for variably controlling said control devices in accordance with the class of the calling line. 85
35. In a telephone system, calling lines arranged in groups according to the class of service to which they are entitled, link circuits individual to each group, control devices common to all groups for controlling the automatic establishment of connections, means responsive to the initiation of a call on one of said lines to cause one of the corresponding link circuits to associate a control device with said line, means on said calling line to set up on said control device a registration of the number of the wanted line, and means in said link circuit for conditioning said control device in accordance with the class of the calling line. 90
36. In a telephone system, calling lines arranged in groups according to the class of service to which they are entitled, link circuits individual to each group, control devices common to all groups for controlling the automatic establishment of connections, means responsive to the initiation of a call by one of said lines to cause one of the corresponding link circuits to associate a control device with said line, means on said calling line to set up on said control device a registration of the number of the wanted line, and means in said link circuit to set up in said control device a registration of the class of the calling line. 95
37. In a telephone system, calling lines arranged in groups according to the class of 100
- 105
- 110
- 115
- 120
- 125
- 130

In witness whereof, I hereunto subscribe my name this 29th day of June, A. D. 1927.

MARTIN L. NELSON.
